UNITED STATES PATENT OFFICE

CHARLES L. DILLINGHAM, OF INDIANAPOLIS, INDIANA

DESIGN FOR A VEHICLE SIGNAL LAMP

Application filed October 24, 1932. Serial No. 45,534. Term of patent 14 years.

To all whom it may concern:

Be it known that I, CHARLES L. DILLINGHAM, a citizen of the United States, residing at Indianapolis, county of Marion, and State of Indiana, have invented a new, original, and ornamental Design for Vehicle Signal Lamp, of which the following is a specification, reference being had to the accompanying drawing, forming part thereof.

Figure 1 is a front elevation, and Figure 2 is an end elevation of a vehicle signal lamp showing my new design.

I claim:

The ornamental design for a vehicle signal lamp, as shown.

CHARLES L. DILLINGHAM.
